UNITED STATES PATENT OFFICE

HARRY K. IHRIG, OF MARTINEZ, CALIFORNIA, ASSIGNOR OF ONE-HALF TO SUMNER E. CAMPBELL, OF ASSOCIATED, CALIFORNIA

PROCESS FOR MAKING AROMATIC NITRO COMPOUNDS

No Drawing.

Application filed January 31, 1927. Serial No. 165,046.

My invention relates to the preparation of aromatic derivatives from hydrocarbon materials.

Briefly stated it consists in the concentration of the aromatic, hydro-aromatic and unsaturated compounds in an extract formed by the treatment of a hydrocarbon material with a polar solvent; the removal of the unsaturated compounds from said extract; and the conversion of the remaining portion either by direct reaction with a reagent to prepare the specific derivative desired, and, or, by oxidizing the hydro-aromatic to aromatic hydrocarbons and subsequently treating these to give the desired derivative.

More particularly, though still somewhat generally stated, the invention comprises the preparation from hydrocarbon material, by treatment with a polar solvent, of an extract consisting of unsaturated, hydro-aromatic and aromatic hydrocarbons concentrated in a relatively small volume; treating said extract with a suitable reagent for the removal of the unsaturated hydrocarbons thereby leaving a remainder comprising a mixture of aromatic, hydro-aromatic and partially hydrogenated aromatic compounds; nitrating said remainder or any distillate fraction thereof; and separating from said nitrated remainder or fraction a mono-nitro compound.

My invention more in detail will now be fully disclosed.

First, as to the preparation of the extract.

A number of crude oils are shown to contain hydrocarbons other than the saturated straight chain hydrocarbons. Such other hydrocarbons may be classified as unsaturated aliphatic, hydro-aromatic and aromatic hydrocarbons. Sometimes hydro-aromatic hydrocarbons are known as napthenes.

In the refining of oils containing such other hydrocarbons than the saturated type of hydrocarbons, there is difficulty using the ordinary methods of refining. In general, the unsaturated, hydroaromatic, and aromatic hydrocarbons can be called polar compounds, as differentiated from the saturated aliphatic, or non-polar hydrocarbons. The fully hy-

drogenated aromatic compounds are midway between the non-polar and polar types.

In order to separate polar hydrocarbons from non-polar hydrocarbons, it is necessary to employ some means other than distillation. One of these means is the extraction with a polar solvent, the polar hydrocarbons going into solution in the polar solvent, and the non-polar hydrocarbons remaining behind as a separate layer. Examples of such polar solvents are liquid sulphur dioxide, liquid ammonia, or liquid hydrochloric acid. These solvents are gases at ordinary temperatures and pressures and hence can be readily removed after the extraction has been made and then can be used for further repetitions of the cycle.

The polar solvent most used in petroleum refining is liquid sulphur dioxide because of its cheapness and relative ease of liquefaction. In using liquid sulphur dioxide the hydrocarbon material is agitated with liquid sulphur dioxide at 15° F. and 1 pound gage pressure. This may be done either in batches, or continuously by having the liquid sulphur dioxide flow counter-currently to the hydrocarbon material. After the liquid sulphur dioxide has become thoroughly mixed in intimate contact with the hydrocarbon material the mixture is allowed to settle. Two layers are observed; a top layer, which consists of the non-polar type of hydrocarbons relatively free of sulphur dioxide, and the lower layer composed of a solution of the polar hydrocarbons and some other impurities, in liquid sulphur dioxide. The lower layer is drawn off and the sulphur dioxide evaporated for further use in the cycle. The upper layer is called raffinat and consists of the non-polar hydrocarbons, and is used either as such or given appropriate additional refining treatment to make high quality refined oil products. The lower layer is known as extract and at present is used for fuel, or for making anti-detonating motor fuel.

The extract is the material referred to herein and is the starting point of my process. It consists of unsaturated, hydro-aromatic, and aromatic hydrocarbons concentrated in a relatively small volume and with relatively

small amounts of inert non-polar hydrocarbons. This material is therefore valuable as the starting point for the production of derivatives of the above mentioned hydrocarbons concentrated in it. In preparing the extract the hydrocarbon material is chosen of appropriate boiling range to make the desired derivatives. In the refining of kerosene the starting material is called kerosene extract. In the refining of cracked gasoline or pressure distillate the material is known as pressure distillate extract.

Any hydrocarbon material may be treated with the polar solvents mentioned above and the extract utilized to give the corresponding derivatives when treated according to the description submitted herein.

In the following example of the succeeding steps of my process, an extract obtained from kerosene by treatment with liquid sulphur dioxide was used.

The extract was first treated with sulphuric acid (93.19% H_2SO_4) for the removal of impurities soluble in this medium, as for example unsaturated hydrocarbons. A combination of these with the acid settled to the bottom of the treating receptacle and was drawn off. This acid sludge can be used for the recovery of alcohol and other valuable products, but for the purpose of this description it is an impurity. The hydrocarbon mixture left after the acid treatment is believed to be a mixture of aromatic, hydro-aromatic, and partially hydrogenated aromatic compounds. This hydrocarbon mixture was fractionated and a 100 c. c. portion boiling from 196° F. to 292° F., by the standard Engler method for gasoline, was nitrated for four hours with a mixture of 100 c. c. concentrated sulphuric acid and 100 c. c. concentrated nitric acid. After the first half hour the temperature was held at 140° to 150° F. Reddish brown fumes were evolved during the treatment. At the end of four hours the mixture was poured on ice and a yellowish brown liquid separated at the bottom of the ice mixture. This, I believe, was the mono-nitro compound, it giving the characteristic odor and being heavier than water. This mono-nitro compound was separated and re-nitrated with 150 gms. of sulphuric acid and 60 gms. of fuming nitric acid. After a couple of hours yellow needle-like crystals separated in the mixed acid mixture. The oil mixture was poured on ice and the yellow crystalline solid was recovered. This was recrystallized from 95% alcohol and was found to have a melting point of 175° C. A mixed melting point determination with 2-5-di-nitro benzoic acid showed no lowering. The compound formed, therefore, was 2-5-di-nitro benzoic acid, the hydrocarbon either having been nitrated directly and a side chain oxidized to form the carboxyl group, or a hydro-aromatic compound was

oxidized to form an aromatic hydrocarbon, which was in turn nitrated, and a side chain oxidized.

Another fraction obtained from kerosene extract boiling from 173 to 181° F. upon nitration as above, gave meta-di-nitro benzene, which upon recrystallization from alcohol melted at 194° F. and showed no change in a mixed melting point with pure meta di-nitro benzene.

Another example of my process with an extract obtained from pressure distillate made by cracking California petroleum gave results similar to the above. From this data it seems that I have both concentrated the true aromatic compounds, which are known to be present in small amounts in petroleum, in the extract, or have oxidized the hydro-aromatic compounds of various degrees of hydrogenation first, and then nitrated the resulting aromatic compound.

While this process has been done experimentally by means of nitration, I believe that other derivatives of aromatic compounds, such as the bromide, chloride, or the free aromatics themselves may be made by concentration, oxidation, and, or, conversion of the aromatic or hydro-aromatic hydrocarbons of petroleum in a relatively small volume of extract. At present these types of compounds are only obtained from coal tar and I believe that the manufacture of them through this process from petroleum constitutes a valuable step in advance.

I claim:—

1. The method of producing a nitro benzene derivative which comprises treating a hydrocarbon distillate containing unsaturated, hydroaromatic, and aromatic compounds with liquid sulphur dioxide to form an extract, separating from said extract the unsaturated hydrocarbon compounds, nitrating the remainder of said extract until the crystalline bodies separate out.

2. The method of producing a nitro benzene derivative which comprises treating a hydrocarbon distillate containing unsaturated, hydroaromatic, and aromatic compounds with liquid sulphur dioxide to form an extract, separating from said extract the unsaturated hydrocarbon compounds, fractionating the remainder to give a cut of approximately 170°-180° F. and nitrating this cut until the crystalline bodies separate out.

3. The method of producing meta-dinitrobenzene which comprises treating a liquid sulphur dioxide extract of a hydrocarbon distillate containing unsaturated, hydroaromatic, and aromatic compounds having a boiling point range of approximately 170°-180° F. with a nitrating agent, until the crystalline bodies separate out and recovering meta-dinitro-benzene.

4. The method of producing 2-5 dinitro benzoic acid, which comprises treating a hy-

drocarbon distillate containing unsaturated, hydroaromatic and aromatic compounds with liquid sulphur dioxide to form an extract, separating from said extract the unsaturated hydrocarbon compounds, fractionating the remainder to give a cut of approximately 195°-290° F., nitrating this cut until the crystalline bodies separate out, and recovering 2-5 dinitro benzoic acid.

10 In testimony whereof I have signed my name to this specification.

HARRY K. IHRIG.
